UNITED STATES PATENT OFFICE.

ARTHUR ENGELBERG, OF OAKLAND, CALIFORNIA.

TELEPHONE-CALL RECORDER.

Application filed March 17, 1924. Serial No. 699,739.

My invention relates to a mechanism for automatically recording telegraphic signals sent over a telephone circuit, such as is shown in my United States Letters Patent No. 5 1,299,154, issued April 1, 1919.

An object of the invention is to provide in a telephonic circuit a telegraphic recording mechanism at a receiver's station adapted to be operated by a sender at some other 10 station or point of the circuit.

Another object of the invention is to provide in a telephonic circuit having an automatic signal recording device at the receiver's end, means for advising the sender 15 of the operation of the receiver's recording device.

A further object of the invention is to provide automatic message recording mechanisms adapted to be operatively connected 20 with a telephone circuit at the sending and receiving stations thereof, whereby duplicate messages may be automatically recorded by said mechanisms upon the sending of a message between said stations.

25 The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I 30 may adopt variations of the preferred form within the scope of my invention as set forth in the claims.

Referring to said drawings:

Figure 1 is a side view of a recording mechanism of my invention.

40 Figure 2 is a plan view of the recording mechanism.

Figure 3 is a plan view of a key used in the operation of the device.

45 Figure 4 is a sectional view of the key taken on the line 4-4 in Figure 3.

Figure 5 is a diagrammatic view showing the recording mechanism and key operatively connected in a telephone circuit.

50 A device which will record a telephone call when there is no person at the receiving station to answer the same is obviously a most desirable adjunct to a telephone system. Since such devices must usually operate without human supervision, their action must be positively assured to the highest possible degree, for their failure to operate

would defeat the purpose of their installation. In accordance with the above mentioned requirement of such recording devices, I have provided recording mechanisms which are 60

adapted to not only record messages in duplicate at both the sender's and receiver's stations, but also to indicate to the sender whether the recording mechanism at the receiver's station is functioning properly. The 65

present embodiment of my invention includes a recording mechanism 7 which is mounted on a base 8 and comprises an electromagnet 9 adapted to operate an armature 11. Fixed to a pivoted arm 12 which is ar- 70

ranged to carry the armature is an extension 13 having at the extremity thereof a point 14 which is adapted to perforate a tape 16 when the armature is actuated by the electro- 75

magnet. The tape is carried on a reel 17 suitably mounted on the base 8 and is adapt- 80

ed to be drawn from the reel and over a fixed support and guide member 18 positioned under the point 14 by means of and between cooperating rollers 21 and 22. Rotation of 85

the rollers 21 and 22 may be effected in any desired manner. As here shown, the roller 22 is mounted on a drive shaft 23 which is actuated by means of a spring operated motor 24 of suitable type. Control of the op- 90

eration of the clockwork is effected by means of a lock pin 26 carried on a spring arm 27 and adapted to normally register with a perforation 28 formed in a gear 29. The gear 29 is operatively connected to the shaft 95

23 by means of a pinion 31. Withdrawal of the lock pin 26 from the perforation 28 is effected by means of an L-shaped lever piv- 100

otally secured to the base 8 and having arms 32 and 33, the former engaging the spring 105

arm 27 and the latter being adapted to be forcibly engaged and moved by the arm 12 when the latter is depressed. In this manner, release of the clockwork and consequent operation of the rollers 21 and 22 is effected upon exciting of the electromagnet by a direct electric current, since the resulting withdrawal of the lockpin 26 from the perforation 28 releases the clock work. Since 110

Movement of the spring arm 27 also serves to close a contact switch 34 which is mounted on the base 8. The switch 34 comprises a movable spring member 36 and a cooperating fixed switch member 37 provided with an adjustable contact point 38. The switch member 36 preferably contacts with the arm 27, thus serving as the means for urging the same toward the gear 29. To insure 10 closing of the switch 34 only while the gear 29 is rotating and at the same time prevent contact between the lever arm 33 and the arm 12 during such rotation, the edges of the gear perforations 28 are preferably bevelled on the side toward the spring arm so 15 that as movement of the gear starts upon the withdrawal of the pin by means of the lever arm 32, the bevelled portion of the gear side will engage the pin obliquely and 20 so wedge the spring arm outwardly until such time as the pin bears on the flat side of the gear. It will thus be noted that closing of the switch 34 is effected only during 25 the rotation of the shaft 23 and the consequent operation of the rollers 21 and 22 to draw tape from the reel.

In Figure 5, a set of recording mechanisms 7 of my invention is diagrammatically shown connected at the two stations 41 and 30 42 of a telephone circuit having line wires 43 and 44, the telephones 45 and their connections being indicated in the conventional manner. For convenience in understanding the operation of the circuit, the sender's key 35 47 at station 41 is shown depressed, and primes are used with the numbers of the parts to indicate corresponding parts at station 42. The key 47 is so constructed, and is here shown so arranged in the circuit, that the 40 closing of the key at the sender's station operates two parallel circuits using the ground as a common return. One of said circuits includes the electromagnet coils of both recording mechanisms, while the other circuit 45 includes the switch 34 at the receiver's station and a signal lamp 48 at the sender's end. In this manner, depression of the sender's key will first effect the release of both spring motors 24 to cause the tapes to 50 be drawn beneath the perforating points, and further depressions of the key will cause perforations to be made in the tapes in synchronism with the operation of the key. Closing of the circuit through the lamp 48 55 is completed only upon the operation of the recording mechanism at the receiver's station to close the switch 34', thus the lighting of the lamp 48 at the sender's station is a positive indication of the operation of the 60 clockwork. To also provide warning if the tape at the receiver's station, because of breakage or exhaustion of the supply, ceases to be drawn beneath the recording point, a suitable switch 49 is provided which is 65 adapted to break the ground circuit at the

receiving station when the tape no longer passes over the support 18. Such switch is preferably, as here shown, mounted on the support 18 and is normally held closed by contact with the tape, the absence of the tape 70 being adapted to cause the displacement of one of the switch members to break the circuit. It will thus be noted that failure of the lamp to flash in synchronism with the operation of the key 47, will be a positive 75 indication of an incomplete operation of the recording mechanism at the receiver's station and the sender is thus warned against sending a message which will not be recorded. 80

As here shown, the key 47 comprises a base 49 on which is mounted a key lever 50 which is adapted to simultaneously touch a pair of contact points 51 and 52 when in normally raised position and a pair of contact points 53 and 54 when in depressed position, the lever 50 being a conductor. For the convenience of a user, and as here shown, the lamp 48 is preferably mounted on the key base 49, the key and lamp being electrically connected to the rest of the device through an extension cable 60 containing the necessary number of conductors. In this manner the key and lamp are adapted to be placed at such distance from the recording 90 mechanism as will bring them close to the telephone instrument in readiness for use in case a sender receives no answer to his telephone call. 95

Assuming that the sender has depressed 100 the key at station 41, and the key at station 42 is in normal position, as indicated in Figure 5, the circuits will be as follows: The telegraphic circuit will lead from a battery 35 at station 41 to contact 53, through key 105 lever 50, to and through the coils of the recording mechanism 7, through a conductor 55 to the line wire 43, through an exchange switchboard 56, through the line wire 43' and conductor 57 to the recording mechanism 7', through the armature of the mechanism 7' and to the key lever 50', through contact 52' and conductor 58' to ground and thence back to battery 35. The signal lamp circuit branches from the telegraph circuit 110 through contact 53, thence leads through the lamp 48 and conductor 59 to the line wire 44, through switchboard 56, through the line wire 44' and conductor 61 to the switch 34' which has closed on account of the starting 115 of the clockwork, thence to the key lever 50' where it rejoins the telegraphic circuit. Since the arrangement of the various switches and the recording mechanisms at 120 each station is identical, it will be obvious that the system here described is reversible in operation. It will be further understood that by repeated depression of the sender's key in accordance with any suitable telegraphic code, a message, such as a telephone 125 130

number, may be recorded on the tape at both the receiving and sender's stations. Furthermore, continued sending will continue to release the spring motor as long as may be needed, whereas the same will be stopped by the stopping means described shortly after sending ceases. By closing a normally open switch 63 in a shunt circuit 64 provided between the terminals of the electro-

10 magnets, the operation of the sender's recording device may be prevented without affecting the remaining operations of the device.

To insure the rewinding of the spring of the clockwork, the tape is preferably marked with some distinguishing symbol such as the words "Wind Clock" at appropriately spaced points along its length. In this manner, the receiver will be warned to keep the 20 spring motor wound to insure the reception of messages.

It will be noted that the device of my invention is particularly applicable to telephone systems of the self-switching or automatic type, and that since in telephoning only alternating currents traverse the line wires, no interference with the functioning of the telephones will result. Since the ground and the two line wires of a telephone 30 system together make three telegraphic circuits available, it will be understood that the exact circuit arrangement here shown is not the only one by which the desired result may be accomplished.

35 I claim:

1. In combination with a recording mechanism for telegraphic signals, means operated by the sender of the signals for causing the operation of the recording mechanism, 40 and an independent signal lamp circuit closable by said mechanism for indicating to the sender the operation of the recording mechanism.

2. A message recording system comprising a self operated recording mechanism at a distant station adapted to record a telegraphic signal, a sounder at said station adapted to be actuated in accordance with said signal and arranged to actuate said recording mechanism, and an inaudible signal operated directly by said recording mechanism for positively indicating the operation thereof at the sending station.

3. In combination with a sounder for indicating telegraphic impulses at a receiving station, a recording mechanism at said station adapted to record said signals, a key at the sender's station for sending said signals, and visible and inaudible signal means 60 at the sender's station operated in synchronism with said impulses by the recording mechanism at the receiving station for positively indicating the operation of the recording mechanism.

65 4. A recording mechanism for electrical

impulses, comprising an electro-magnet adapted to be energized by said impulses, a lever adapted to be actuated by the magnet, a recording means operable by movement of the lever, record tape arranged to 70 be contacted by said recording means, a normally inoperative motor adapted to draw said tape through said recording means, means operable by said lever for temporarily releasing said motor, and a signal lamp 75 at the station of the sender operable by said motor releasing means for indicating the operation of said motor.

5. A recording mechanism for electrical impulses, comprising an electro-magnet, a 80 lever arranged to be actuated by the magnet, a recording means actuated by the lever, record tape arranged to be contacted by said recording means, a motor for feeding the tape from the reel, a wheel rotated by the 85 motor and having a recess therein, a spring arm having a lock pin thereon normally engaged in said recess to prevent the operation of the motor, a pivoted releasing lever engaging with said spring arm and arranged to be operated by said first lever to withdraw the lockpin from said motor wheel recess to temporarily release the motor, and a contact switch operated by said motor releasing lever while the motor is operating. 95

6. The combination with a telegraphic circuit having an automatic recording mechanism at the receiver's end thereof of a second circuit including a lamp at the sender's end arranged to be closed during the operation of the first circuit whereby the sender 100 may be visually advised of the operation of the recording mechanism.

7. In combination with a telegraphic circuit, automatic recording mechanisms at the 105 sending and receiving stations thereof whereby duplicate message may be automatically recorded by said mechanisms upon the sending of a message between said stations and the operation of the recording 110 device at the receiving station will be indicated at the sending station independently of the recording mechanism thereat.

8. In combination with a telegraphic circuit having a sender's station and a receiver's station, an automatic recording mechanism at the receiver's station, an electric signal circuit associated with and operable independently of said telegraphic circuit, a signal arranged in said signal circuit at the 115 sender's station, and means operable by said mechanism at the receiver's station to close said signal circuit only during the operation of said recording mechanism.

9. In combination with a telegraphic circuit having a sender's station and a receiver's station, an automatic recording mechanism at the receiver's station, an electric signal circuit associated with and operable 120 independently of said telegraphic circuit 125

130

- cuit, a signal arranged in said signal circuit at the sender's station, a record tape arranged to be drawn through said recording mechanism, and a switch arranged in said signal circuit and adapted to be actuated by said recording mechanism to prevent the closing of said signal circuit when no tape is in position to have messages recorded thereon.
- 10 10. In combination with a telegraphic circuit having a sender's station and a receiver's station, an automatic recording mechanism at the receiver's station, a record tape arranged to be drawn through said recording mechanism, a normally inoperative re-

leasable motor associated with said recording mechanism and arranged to draw said tape therethrough, an independent signal circuit between said stations, a switch in said signal circuit adapted to be actuated to cause the closing thereof by and upon the operation of said motor, and a second switch in said circuit arranged to prevent closing of said circuit when said tape is removed from operative relation to the mechanism. 20

In testimony whereof, I have hereunto set my hand at Oakland, California, this 15th day of February, 1924.

ARTHUR ENGELBERG.
